US0D1063938S

(12) **United States Design Patent** (10) **Patent No.:** **US D1,063,938 S**
Xing (45) **Date of Patent:** **** Feb. 25, 2025**

(54) **KEYBOARD**

(71) Applicant: **Leiju Electronic Technology (Dongguan) Co., Ltd.**, Guangdong (CN)

(72) Inventor: **Jian Xing**, Guangdong (CN)

(73) Assignee: **Leiju Electronic Technology (Dongguan) Co., Ltd.**, Guangdong (CN)

(**) Term: **15 Years**

(21) Appl. No.: **29/894,669**

(22) Filed: **Jun. 13, 2023**

(30) **Foreign Application Priority Data**

Mar. 22, 2023 (CN) 202330139754.5

(51) **LOC (15) Cl.** **14-02**

(52) **U.S. Cl.**

USPC **D14/393**

(58) **Field of Classification Search**

(57) **CLAIM**

The ornamental design for a keyboard as shown and described.

DESCRIPTION

FIG. 1 is a front, left and bottom perspective view of a keyboard, showing my design.

FIG. 2 is a rear, right and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is an enlarged view of detail 9 in FIG. 1.

The even-dash broken lines depict portions of the keyboard that form no part of the claimed design.

The dot-dash broken lines in FIGS. 1 and 9 represent the limits of the enlarged detail view and form no part of the claimed design.

1 Claim, 9 Drawing Sheets
